UNITED STATES PATENT OFFICE.

STEPHEN I. FEKETE, OF DETROIT, MICHIGAN, ASSIGNOR TO HUDSON MOTOR CAR COMPANY, OF DETROIT, MICHIGAN, A CORPORATION OF MICHIGAN.

DESIGN FOR A GAS-ENGINE CASING.

47,689.

Specification for Design.

Patented Aug. 10, 1915.

Application filed January 21, 1915. Serial No. 3,645. Term of patent 14 years.

To all whom it may concern:

Be it known that I, STEPHEN I. FEKETE, a citizen of the United States, residing at Detroit, county of Wayne, State of Michigan, have invented a certain new, original, and ornamental Design for Gas-Engine Casings, of which the following is a specification, reference being had to the accompanying drawings, which form a part of this specification.

The figure is a perspective view of a gas engine casing showing my design.

Copies of this patent may be obtained for five cents each, by addressing the "Commissioner of Patents, Washington, D. C."

I claim—

An ornamental design for a gas engine casing as shown.

In testimony whereof, I sign this specification in the presence of two witnesses.

STEPHEN I. FEKETE.
